UNITED STATES PATENT OFFICE.

ABRAM EMERSON MINIUM, OF DENVER, COLORADO.

COMBINED DRIVING AND STEERING MECHANISM.

1,265,358.

Specification of Letters Patent.

Patented May 7, 1918.

Application filed May 12, 1916. Serial No. 97,144.

To all whom it may concern:

Be it known that I, ABRAM EMERSON MINIUM, a citizen of the United States, residing at the city and in the county of Denver 5 and State of Colorado, have invented certain new and useful Improvements in Combined Driving and Steering Mechanism; and I do hereby declare the following to be a full, clear, and exact description of the invention, 10 such as will enable others skilled in the art to which it appertains to make and use the same.

This invention is for improvements in driving and guiding mechanism for rotary 15 propelling bodies, and is more particularly applicable to the propellers of aerial and submersible submarine craft, where effective dirigibility must provide for vertical deviations of course, at varying angles and curves, 20 as well as lateral steering.

Without going into unnecessary details at the beginning, it is believed that the utility, 25 objects and advantages of the invention will fully appear from the following description, the same consisting of the structural arrangement and combination of elements, which will now be described, the essential features of novelty being more succinctly stated in the appended claims.

30 In the specification, reference is had to the accompanying drawings, forming a part of this application, in which drawings like characters designate the same parts in the several views, and in which—

35 Figure 1, is a vertical sectional view taken axially of the mechanism, the parts being in their normal positions, with the driving gears shown in edge elevation, and the segmental rack and pinion steering elements shown in section.

40 Fig. 2, is a central vertical transverse sectional view through the spherical casing, taken along the line 2—2 of Fig. 1.

Figs. 3, 4 and 5, are cross-sectional views 45 on the lines 3—3, 4—4, and 5—5, respectively, and looking in the directions of the arrows.

50 Fig. 6, is a plan view of a propeller in the position it would be thrown in steering to the right.

Fig. 7, is a similar view to Fig. 6, showing the reverse position of the propeller, steering to the left, and.

55 Fig. 8, is a plan view of the propeller, but with the hub spindle thereof disposed at an

inclination substantially 45° from both central vertical and horizontal planes, when the course would be in a combined vertical and lateral direction.

If Fig. 6 be viewed as a side elevational view, it shows the position of the propeller, when a dipping or diving course is being pursued, and Fig. 7, similarly viewed shows a reversal of the course in an ascending direction. Fig. 8 simply illustrates one of the 65 variable steering positions between the extremes in a combined lateral and vertical course.

It will be understood that any number and arrangement of propellers may be employed, but my invention being for a mechanism local to the propeller itself, I have simply shown it in unitary relation.

1 designates the driving shaft, suitably coupled to the motive power in any well known way, designated conventionally by a shaft coupling 2. The driving shaft is preferably hollow, and may form part of a lubricating system, not shown.

3 is a hollow steering shaft for swinging 80 the pivotal support for the hub spindle, and 4 is a similar hollow shifting shaft for bodily rotating the support to which the hub spindle support is pivoted, all of which will be more fully set forth.

85 The hollow shaft 3 envelopes the driving shaft 1, and the hollow shaft 4 encompasses the shaft 3, the shaft 4 in turn being contained and journaled in a bearing sleeve 5, held against rotation in any suitable way, 90 shown simply by the projecting parts 6, provided with bolt holes for securing purposes.

The several shafts are arranged in self-contained stepped relation, the outer ends of the shafts 3 and 4 being provided with 95 controlling means, such as the rack 7 and pinion 8 for the shaft 3, and the worm wheel 9 and worm 10 for the shaft 4, operated from any suitable station. Manifestly other suitable well known controlling means 100 may be used and would be equivalent.

Where desired, anti-friction means may be provided between the several shafts, respectively, and the bearing sleeve, and the spaces between the shafts may be suitably 105 packed, but as these are obvious expedients, I have simply illustrated roller bearings 11 in a wholly conventional way.

12 designates a forked member or support, forming a part of an open knuckle joint, 110

the other member 13 of which is of substantially similar construction and provides a pivotal journal bearing for the hub spindle.

It is obvious that these open or forked members 12 and 13 may be of varying contour, whether rectangular or otherwise, provided that sufficient space is provided within the open knuckle joint to seat certain elements, as will presently appear.

- 10 The members 12 and 13, however, are preferably semi-cylindrical arms, recessed at their ends to form an overlapping joint, the abutting portions 14 of the curved arms being struck at a proper arc to enable 15 the member 13 to swing on an axis pin 15 hinging the two arms centrally, which axis pin is disposed in radial alinement with the propeller blades, for important reasons hereinafter referred to.
- 20 The details of securing this axis pin, however, are not materially important, the pin being shown simply as having a counter-sunk head, and a threaded end engaged by a counter-sunk nut 16 for effective neatness. It will be understood, however, that 25 the arms 12 are sufficiently rigid to prevent the axis pin 15 from causing them to bind the semi-circular arms 13, which are free to swing on the axis pin, under proper 30 control.

The arms 12 are rigidly mounted fast on the inner end of the tubular shaft 4, and are preferably provided with an annular nipple or rim 17.

- 35 The pivotal member 13 is provided axially with a cylindrical boss 18, bored to journal the hub spindle 19, which may be squared at its outer end 20 to support the hub 21, which may be hollow and of substantially semi-spherical contour, provided 40 with radial studs or projections 22, representing spokes or supports for propeller blades 23. The solid central portion of the hub is apertured to fit over the squared 45 end 20 of the hub spindle, and may be held fast thereon by any suitable means, as by a lock nut 24. This central portion of the hub may also be properly recessed to house the cylindrical boss 18.
- 50 Mounted fast on the inner end of the hub spindle is a bevel gear 25, meshing with a bevel pinion 26, loosely journaled on the axis pin 15, and in turn meshing, as an intermediate gear, with a bevel gear 27, 55 fast on the inner end of the tubular driving shaft 1.

- These gears preferably have convex rear surfaces for neat and snug seating, and the gear 27 seats revolvably within a dished or 60 concave shift pinion 28, mounted fast on the inner end of the tubular steering shaft 3, and meshing with a rack element 29, secured fast on the inside face of one arm of the pivotal member 13.
- 65 30 may be termed a spacing sleeve, be-

tween the circular rack element and the loose bevel pinion 26, freely encompassing the axis pin 15 which is rigidly fixed.

The contour of the inner surfaces of the members 12 and 13, and the outer surfaces 70 of the inclosed circular rack and pinion elements are such that snug seating is attained.

On the rim or collar 17 is fixedly seated a similar collar 31 of a shell member 32, 75 of segmental globular structure, coöoperating with an oppositely disposed substantially similar shell member 33, of slightly greater diameter, and provided with a projecting sleeve 34, loosely mounted on the cylindrical boss 18 between the latter and the recessed solid central portion of the hub 21.

These two shell sections are assembled in overlapped relation to form an effective spherical casing or housing, to protect the 85 interior mechanism against accident, and from being clogged up by mud or other foreign substances, but the member 33 is free to roll or turn in all directions relatively to the member 32, with the latter as 90 a bearing, after the fashion of a universal joint of the ball and socket type.

In order that the shifting of the hub to varying positions will not displace the spherical housing sections sufficiently to 95 partially separate them, and to more positively hold them in such universal articulated relation, the shell 33 may be profitably provided with a supplementary ring section 35, following the spherical curvature of the 100 section 33, and this auxiliary member may be secured to the shell 33 in any suitable way, such as by the integral annular flanges 36 and 37, on the respective parts, provided with apertures 38, and secured together by 105 bolts 39. The diameter of the opening 40 of the ring member 39 being less than the diameter of the shell 32, separation of the housing sections is prevented, it being observed that the peripheral length of each 110 segmental shell is greater than its semi-circumference.

41 simply designates feathers for keying certain elements together as shown.

It may be noted that the axis pin 15 is 115 located intermediate of the bevel gears 25 and 27, being disposed at right angles to the spaced ends of the hub spindle and driving shaft, and always lies in a plane coincident with the plane of rotation of the 120 propeller blades, in whatever position they may be rotated. The axis pin is also located interiorly or centrally within the periphery of the propeller blades, as contradistinguished to an axis pin located outside of the 125 periphery.

From the drawings and the foregoing description, the operation of the mechanism is fairly apparent, but it may be said that the axis pin 15 may be set at any effective 130

- angular position, within its axial plane, and held in that position, it being supported by the member 12, fixed to the hollow shaft 4, controlled by the worm gearing 9—10. 5 Hence the propeller may be operated not only to steer to the right or left, or up and down, but also in a combined relation both laterally and vertically at varying angles, one position of the propeller for steering in 10 such combined relation being shown in Fig. 8, wherein the vessel's course would be substantially upwardly and to the right.

As shown in Fig. 1, the axis pin is disposed vertically. In that position, to steer 15 to the right or left, the propeller may be moved to varying vertical planes, between the positions substantially shown in Figs. 6 and 7, when viewed as plan views. This is accomplished by the rack and pinion 7—8, 20 controlling the steering shaft 3, which carries the pinion 28, meshing with the circular rack element 29, fixed to the member 13, carrying the hub spindle 19 and the housing section 33, the hub spindle gear 25 rolling 25 idly around the bevel pinion 26, and the concave surfaces of the housing section 33 and 35 moving around over the convex surface of the section 32, with the free sliding movement of a ball and socket articulation. This 30 obviously does not interfere with the propelling mechanism, including the driving shaft 1, its bevel gear 27, pinion 26, and the hub bevel gear 25, which gears and intermediate pinion are always in mesh.

35 When it is desired to steer in an ascending or descending course, at varying inclinations, the worm wheel 9 is operated to turn the axis pin 15 a quarter revolution, to the right or left as desired, in its own 40 axial plane, or at right angles to the shafting, when the axis pin will be disposed horizontally, and the steering elements 7—8 may be operated, as before described, to shift the propeller bodily in a vertical arc, at varying 45 angles between those indicated by Figs. 6 and 7, when viewed as side elevational views, to cause the vessel to dive or rise, respectively.

At all of the positions at which the axis 50 pin is set, it will be observed that the plane, containing the axial lines of the propeller blades, is always coincident with a plane passing through the axis pin, so that in operating the steering shaft 3, and its elements, the plane containing the propeller 55 blades turns on its own diametral axis, coincident with the axis pin, and hence there is no lost motion, as would be the case where the propeller was swung around bodily on a 60 pivot outside of or distant from the plane containing the blades. It is believed to be manifest that, by this particular arrangement, steering is made much easier, as less power is required to be applied at the steering 65 wheel.

This arrangement also permits of the thrust of the propeller being directed forwardly of the axis pin or on the parts in advance of same, in any position of the propeller, and not on the hub spindle, when 70 swung out of direct axial line with the driving shaft, thus preventing undue strains on the gears and supporting parts, which is obviously important.

Also in marine navigation, it may be 75 noted as an advantage that, where a vessel is grounded, bow on for instance, the propeller may be adjusted, so that power may be applied to pull down on the stern at any angle, thus tending to elevate the bow while 80 backing off.

I am aware of the fact that the mere form and arrangement of the gears 25, 26 and 27, are not in themselves new, and I make no 85 distinct claims to them alone, and in fact my invention is not limited to the precise details shown and described, but is intended to cover a full range of equivalents as reasonably come within the scope of the ensuing claims. 90

Having thus described a practical embodiment of my invention, however, what I do claim is:—

1. Operating mechanism for propellers, including driving and steering shafts mounted 95 in self contained relation, a tubular shifting shaft surrounding same, and means for separately operating said shafts, in combination with an inner forked member fixed to said shifting shaft, and an oppositely disposed similarly forked outer member, the adjacent 100 projecting ends of which members are pivotally connected to each other; a hub spindle journaled by said outer member; a propeller mounted on said hub spindle; a segmental 105 rack interiorly fixed to said outer member; a pinion element meshing with said rack, and fixedly secured to said steering shaft interiorly of said members; and universally operating connections between said driving 110 shaft and hub spindle, substantially as described.

2. Operating mechanism for propellers, including a driving shaft, a tubular shifting shaft, an intermediate tubular steering shaft, 115 and operating means therefor, in combination with an inner semi-circular support affixed to said shifting shaft, and an oppositely disposed similar outer support, the adjacent ends of which supports overlap and 120 are pivotally connected to each other; a hub spindle journaled by said outer support; a propeller mounted on said hub spindle; a segmental rack interiorly fixed to said outer support; a concavo-convex pinion element 125 meshing with said rack and affixed to said steering shaft, with its convex face contiguous to the inner surface of said inner support; a convex-backed bevel gear fitting within the concave face of said pinion ele- 130

ment and affixed to said driving shaft; a bevel gear affixed to said hub spindle; and an intermediate idle bevel gear meshing with said aforesaid gears, substantially as described.

3. Operating means for propellers, including a driving shaft, a tubular shifting shaft, an intermediate tubular steering shaft, and rotating means therefor, in combination with an inner forked member fixed to said shifting shaft, and an oppositely disposed similarly forked outer member, the adjacent ends of which overlap and are pivotally connected to each other; a hub spindle journaled by said outer members; a propeller mounted on said hub spindle; a segmental rack affixed to the interior of said outer member; a pinion element meshing with said rack and affixed to said steering shaft interiorly of said members; universally operating connections between said driving shaft and hub spindle; and a segmentally formed globular housing completely incasing said forked members, the open ends of the segments thereof overlapping in closed sliding relation, with the inner segment fixed to and rotatable with said shifting shaft only, while the outer segment is carried by said outer forked member and freely movable therewith in all directions, substantially as described.

4. In operating mechanism for propellers, the combination of a driving shaft; an inner

forked support rotatably mounted adjacent the inner end of said shaft; an oppositely disposed similarly forked outer support, having its projecting ends located in overlapped relation with the complementary ends of said inner support; pivoting means therebetween lying in a plane at right angles to said driving shaft; means for rotating said inner support for shifting said pivoting means in its own axial plane; means for swinging said outer support around its pivotal axis, including rack and pinion elements positioned interiorly of said forked supports; a hub spindle journaled by said outer support; means universally connecting the inner ends of said hub spindle and said driving shaft; a segmentally formed globular housing, completely incasing said forked supports and contained mechanism, the open ends of the segments thereof overlapping in closed sliding relation, functioning as a ball and socket articulation, and the outer segment being carried by said outer forked support, being freely movable therewith in all directions; and a propeller hub element mounted on said hub spindle and supporting the plane of its propelling blades in axial alinement with said pivoting means, substantially as described.

In testimony whereof, I affix my signature.

ABRAM EMERSON MINIUM.
